COFFEE MAKER

Denis J. Jordan, Eau Claire, Wis., assignor to National
Presto Industries, Inc., Eau Claire, Wis.

Filed Sept. 15, 1971, Ser. No. 180,938

Term of patent 14 years

Int. Cl. D7—04

U.S. Cl. D7—65

Fig. 1.

Fig. 2.

Fig. 4.

Fig. 3.

Fig. 5.

Fig. 6.

Fig. 7.

FIG. 1 is a side elevational view of a coffee maker showing my new design;

FIG. 2 is a front elevational view of the coffee maker;

FIG. 3 is a rear elevational view thereof;

FIG. 4 is a top plan view thereof;

FIG. 5 is a bottom plan view thereof;

FIG. 6 is a partial vertical sectional view on an enlarged scale taken on line 6-6 of FIG. 4 looking in the direction indicated by the arrows; and

FIG. 7 is a horizontal sectional view taken on lines 7-7 of FIG. 6.

I claim:

The ornamental design for a coffee maker, substantially as shown.
